UNITED STATES PATENT OFFICE.

FRANK L. JOHNSON, OF CHICAGO, ILLINOIS, ASSIGNOR TO GLEASON-TIEBOUT GLASS CO., OF NEW YORK, N. Y., A CORPORATION OF NEW YORK.

DESIGN FOR A GAS AND ELECTRIC LIGHT SHADE.

No. 38,747.

Specification for Design.

Patented Aug. 13, 1907.

Application filed July 8, 1907. Serial No. 382,799. Term of patent 7 years.

To all whom it may concern:

Be it known that I, FRANK L. JOHNSON, a citizen of the United States, and residing at Chicago, in the county of Cook and State of Illinois, have invented a new, original, and ornamental Design for Gas and Electric Light Shades, of which the following is a specification, reference being had to the accompanying drawing, forming part thereof.

The figure is a perspective view of a gas

and electric light shade, showing my new design.

I claim:—

The ornamental design for a gas and electric light shade, as shown.

FRANK L. JOHNSON.
